ROLAND A. FURLONG, OF ROCHESTER, NEW YORK, ASSIGNOR TO THE YAWMAN & ERBE MANUFACTURING COMPANY, OF ROCHESTER, NEW YORK, A CORPORATION OF NEW YORK

VISIBLE INDEX

Application filed November 26, 1929. Serial No. 409,771.

This invention relates to visible index systems and is concerned particularly with improvements in the means for mounting a card tray. One of the objects of the invention is to mount a tray for visible index cards hingedly on a slidable carrier, the parts being so related to the container for the tray that it may readily be moved in and out and when exposed can be supported conveniently for posting in a position most convenient to the operator. Another object of the invention is to provide in association with the supporting means mechanism for automatically elevating the top card when the tray is in working position so that the visible index cards can be more readily manipulated without interference by the top card. This improved mechanism, conversely, insures the restoration of the top card to its normal position automatically when the tray is moved back into its container. Another object of the invention is to simplify all of the parts which are associated for the purposes indicated above reducing their cost of manufacture and facilitating their assembly and disassembly while insuring the most convenient operation in use. A further object of the invention is to improve the construction of a visible index cabinet in which the improved trays are supported slidably whereby the door for the cabinet itself may be employed to advantage as a shelf to support a card tray in the most convenient angular position when it is in use. The improved cabinet, further, is fabricated from a plurality of metal parts so assembled and nested that they will be retained in their intended relation without the necessity of employing positive connecting devices or welding except for the shell of the cabinet itself.

These and other objects are attained by means which will be described more particularly in connection with the embodiment illustrated in the accompanying drawing, wherein:

Figure 1 is a view in front elevation of a cabinet constructed in accordance with the invention, part of the door and front framing being broken away to show the way in

which the supporting means for the trays are built up.

Figure 2 is a view in side elevation of the improved cabinet with one of the trays withdrawn for use and supported in angular position on the cabinet door, the side wall of the cabinet being broken away to show the relation of a series of trays.

Figure 3 is a fragmentary detailed view in side elevation showing a tray in horizontal position and the relation between its supporting means and the top card.

Figure 4 is a fragmentary view in plan of the tray shown in Figure 3 and taken on the plane indicated by the line 4—4 of Figure 3, the supporting ways for the tray hanger being illustrated in section.

The cabinet may be formed of an external shell *a* and within that may be supported at each side a series of pressed metal ways *b* 70 each one of which is formed with a longitudinally extending groove *b'* for purposes to be described later. Between each of the ways is disposed a flat partition *c*. The number of such ways and partitions will equal the number of trays to be mounted within the cabinet. At the front of the cabinet is provided an opening to receive a vertically disposed door *d* which is hinged by pins *d'* at its lower edge so that it may be swung outwardly and downwardly to expose the trays within. At the bottom of the cabinet at each side thereof are disposed opposed channels *e* in which the pins *d'* may slide when the door is slid inwardly in a horizontal position within a recess which is formed beneath the trays for that purpose. The front wall of the cabinet adjacent the opening provided for the door *d* may be flanged with a reverse bend as indicated at *a'* to constitute an end wall for the series of ways *b* and to limit the outward movement of the tray support as will be described later.

One of the card trays is illustrated in Figure 2 at *f*. A finger pull *f'* may be provided at its front end. This tray at its rear end carries upstanding lugs *f''* at opposite sides through which may pass retractile retaining pins *g*. The carrier for the tray is formed as a generally U-shaped wire frame *h* having reversely bent legs *h'* adapted to be received

slidably within the longitudinal grooves b' in opposed ways b at opposite sides of the cabinet. The carrier h is engaged with the up-standing lugs f^2 by means of the pins g which may be retracted to disengage the tray from its carrier if it is desired to remove it entirely. Referring now to Figures 2 and 4 it will be apparent that the interengagement of the pins g with the carrier h forms a hinged connection for the tray f when withdrawn from the cabinet so that it may drop down into convenient working position. When the tray is to be restored to the cabinet it is raised to a horizontal position and moved rearwardly. When the lugs f^2 on the tray engage the loops in the reverse bends of the carrier h continued movement of the tray will force the carrier rearwardly in its supporting ways b to a point where the tray is completely housed. Contrariwise, when the tray is pulled forwardly for use the pins g will slide along the legs of the carrier h until the lugs f^2 engage the forward bends in the carrier whereupon continued movement of the tray will cause the carrier legs h' to slide in the grooves b' to the forward position indicated in Figure 4. This forward movement of the carrier is positively arrested by engagement of the ends of the legs h' with the front wall a' of the cabinet. A further feature of the construction resides in the use of the door d as a shelf for supporting any one of the trays when withdrawn in desired working position. By dropping the door forwardly and downwardly to horizontal position it can be slid rearwardly to a slight extent within the recesses provided for it in the cabinet where it is firmly held as indicated in Figure 2. When a tray is then withdrawn it can be lowered on its hinged support until it rests on the forward edge of the door d . It is generally the practice to provide a top card for visible index trays which normally rests flat on the bank of cards to hold them snugly in position while the tray is being moved in and out. Such a top card is illustrated at i and is shown as pivoted on a cross rod i' , at the rear end of the tray. In accordance with the invention this top card is also formed with a forwardly extending flange i^2 which is parallel to the top card i but spaced therefrom as shown in Figure 2. The spacing of this flange i^2 is such that when the tray is retracted the carrier h engages the flange i^2 so that continued movement of the tray results in the top card i being thrown up from the visible index cards through the inter-engagement of the carrier h with the flange. The same action occurs when the tray is dropped to an angular position. In Figure 3 the top card is shown in normal position and the relation of the flange i^2 to the carrier h is clearly indicated, the tray at this moment being in horizontal position. When the tray is dropped angularly it will be ap-

parent that it moves about its pins g as a center while the carrier h remains stationary. The pivotal support i' for the top card i and the flange i^2 likewise moves on an arc about the center g , the result being that the flange itself moves relatively to the carrier h and is thrown upwardly as shown in Figure 2. When the tray is restored to horizontal position the contrary action occurs and the top card is permitted to drop by gravity into its normal flat position on the index cards at which time the tray can be slid rearwardly into the cabinet.

It will be evident that changes in the details of construction can be made particularly in respect to the character of the hinges and pivots employed and the precise form of carrier and its ways. Changes in design are to be deemed within the scope of the invention so long as they fall under the appended claims.

What I claim is:

1. A carrier for a slidable tray comprising a horizontally disposed U-shaped member having reversely extending legs in the same plane therewith for movement in supporting ways.

2. A carrier for slidable trays comprising a horizontally disposed U-shaped wire to support the tray and having its ends reversely bent to provide legs in the same plane to be slidably mounted in supporting ways.

3. In combination with a slidable tray, an integral U-shaped carrier to support the tray having opposed portions formed therewith and reversely bent at their ends for sliding engagement in ways and means to engage the tray hingedly with the carrier.

4. In combination with a slidable tray an integral U-shaped carrier to support the tray having opposed portions reversely bent at their ends for sliding engagement in ways and releasable means to connect the tray hingedly and positively with the carrier.

This specification signed this 19th day of November A. D. 1929.

ROLAND A. FURLONG.
